UNITED STATES PATENT OFFICE.

GEDALIA RABINOWITZ, OF ARVERNE, NEW YORK, ASSIGNOR TO VENUS LIGHTING FIXTURE CORPORATION, A CORPORATION OF NEW YORK.

DESIGN FOR A LIGHTING-FIXTURE BACKPLATE.

Application filed January 12, 1927. Serial No. 20,357. Term of patent 3½ years.

To all whom it may concern:

Be it known that I, GEDALIA RABINOWITZ, a citizen of the United States, and a resident of Arverne, county of Queens, and State of New York, have invented a new, original, and ornamental Design for a Lighting-Fixture Backplate, of which the following is a specification, reference being had to the accompanying drawing, forming a part hereof.

In these drawings:

Figure 1 is a front elevational view of the lighting fixture back plate;

Figure 2 is a top plan view of the same, and

Figure 3 is a side elevational view with parts shown in section along the line 3—3, of Figure 1.

The back plate is characterized by a number of window openings *a* which overlie a translucent sheet or plate *b*.

I claim:

The ornamental design for a lighting fixture backplate substantially as shown and described.

GEDALIA RABINOWITZ.
